US0D1095669S

(12) United States Design Patent (10) Patent No.: US D1,095,669 S
(45) Date of Patent:  Sep. 30, 2025

(54) TYPE FONT(71) Applicant: Apple Inc., Cupertino, CA (US)(72) Inventors: Ian V. Bambao, Pittsburg, CA (US);
Aurelio Guzmán, San Jose, CA (US)(73) Assignee: Apple Inc., Cupertino, CA (US)() Term: 15 Years(21) Appl. No.: 29/913,769(22) Filed: Oct. 9, 2023*Related U.S. Application Data

(63) Continuation of application No. 29/858,429, filed on Oct. 31, 2022, now Pat. No. Des. 1,004,697, which is a continuation of application No. 29/707,738, filed on Sep. 30, 2019, now Pat. No. Des. 968,506.

(51) LOC (15) Cl. ..... 18-03(52) U.S. Cl.USPC ..... D18/27; D14/495(58) Field of Classification SearchUSPC D14/492, 495; D18/24-28, 32, 33
CPC G09B 11/00; G09B 11/04; G09B 17/00;
